UNITED STATES PATENT OFFICE.

CHARLES F. BURGESS, OF MADISON, WISCONSIN, ASSIGNOR TO BURGESS BATTERY COMPANY, OF MADISON, WISCONSIN, A CORPORATION OF WISCONSIN.

BATTERY HAND LAMP.

1,421,399.

Specification of Letters Patent.

Patented July 4, 1922.

Application filed May 14, 1920. Serial No. 381,245.

To all whom it may concern:

Be it known that I, CHARLES F. BURGESS, a citizen of the United States, residing at Madison, in the county of Dane, State of Wisconsin, have invented certain new and useful Improvements in Battery Hand Lamps; and I do hereby declare the following to be a full, clear, and exact description of the invention, such as will enable others skilled in the art to which it appertains to make and use the same.

Battery hand lamps as ordinarily constructed throw a rather concentrated beam of light of relatively small diameter. For some purposes, as for work at a desk, or around machinery, a more diffused light is desirable.

It is one of the objects of the present invention to provide a battery hand lamp so constructed that it easily can be converted for use in delivering diffused light, or the usual concentrated beam, as occasion requires. To this end the reflector for the lamp is of special construction and is removable with the lens and lens-supporting ring to leave an operative battery lamp adapted like the ordinary candle for distributing light in substantially all directions.

It is a further object of the present invention to so mount the lamp and its associated parts that they are readily accessible for adjustment or renewal.

It is a further object of the present invention to provide a resilient mounting of the lamp, preferably in the form of a yielding support for the lamp socket, whereby shocks and blows from the battery against the inner and fragile terminal of the lamp are in a measure cushioned or absorbed.

It is a further object of the present invention to so mount the lens and reflector in the lens-supporting ring or head, that on removal of the head, all of these parts come off together without disturbing the operative relation of the lamp to the battery, and can be reinstalled without inconvenience or difficulty.

Further objects and advantages will be made clear by the following detailed description, which is to be taken in conjunction with the accompanying drawings, where-

in—

Figure 1 is an elevation of a battery can-

dle to which a lens-supporting ring can be added if a concentrated beam of light is desired;

Fig. 2 is a sectional elevation through a complete hand lamp; and

Fig. 3 is a view of the front end of the hand lamp with the enlarged head and its lens and reflector removed.

In the particular embodiment illustrated in the drawings, the dry cells 1 and 2, of which any suitable number may be provided, are arranged end to end in series relation within a paper tube 3. The naked bottom of the lowermost dry cell is electrically connected through a helical spring 4 with a metal bottom cap 5 screw-threaded to the lower end of the tube 6 which forms the casing of the hand lamp. This tube 6 may be of metal or of fiber, in accordance with the usual practice. At the front end of tube 6 is a metal collar 7 preferably attached permanently to the tube, as by rivets 8. This collar 7 may have its front edge turned inward to form a retaining flange 9.

At the front end of the casing so formed, and preferably attached thereto permanently, as by screw-threading into collar 7 before the latter is riveted to tube 6, is an insulating disc 10. This is preferably made of soft rubber or equivalent yielding and insulating material. Through a central opening in this insulating disc protrudes a lamp 11 with its inner terminal 12 in contact with and therefore in electrical connection with a terminal 13 of the battery of dry cells. The lamp is provided with a socket 14 in which it is suitably secured, as by screw threads. Mounted in the insulation and contacting with socket 14 is a pin or screw 15, serving as a conductor with which a sliding finger 16 may make connection in usual manner when the lamp is to be lighted. A sliding push button 17 suitably mounted on the casing serves as a means for controlling movement of the contact finger 16. Other forms of switch mechanism can of course be used in completing the connection from the bottom terminal of the battery through spring 4 and cap 5 to lamp socket 14.

The structure above described is a completely operative battery candle for giving diffused light in practically all directions,

and the lighting of the lamp by the battery current is under full control of the switch mechanism and its actuating button 17.

In addition to the structure above described, there may be and preferably is provided a detachable head, one embodiment of which is illustrated in Fig. 2. The head there shown comprises a threaded portion 18 engaging with threads on collar 7, a flaring portion 19, and a cylindrical portion 20, on 10 a shoulder 21 of which is seated the flange of a reflector 22. A lens 23 is seated on the reflector flange and the front edge of the sheet metal head is spun over at 24 to permanently grip the lens and hold it and the reflector permanently in position.

The center of reflector 22 has an opening larger than the bulb of lamp 11, so that the head may be unscrewed and removed from 20 the casing without disturbing the operative relation between the battery and the lamp. The lamp socket 14 may have its upper edge flared outwardly to serve as a small reflecting surface, but the socket has a diameter 25 smaller than that of the opening in the reflector so that an air gap intervenes at all times to insulate the reflector from the socket.

With the arrangement above described, the usual concentrated beam of light is 30 thrown by the hand lamp when the switch is closed at screw 15, and if a diffused light is desired, the flaring head is removed to convert the hand lamp into the battery candle shown in Fig. 1. This adjustment may 35 be made even when the lamp is burning and without disturbing in any way the normal operative relation between the battery and the incandescent lamp. If but a slight alteration in the beam of light is desired, this 40 may be effected by partially unscrewing the head, for by so doing, the reflector shifts with respect to the lamp, changing the focal distance, with resultant change in the character of the beam delivered by the hand 45 lamp.

The facility with which the hand lamp can be taken apart and put together is of great convenience to the user, and particularly to a salesman demonstrating the device to a prospective purchaser, for the reflector and the lens, are always held in proper operative relation to the enlarged head and do not get scattered around. Also, in putting the parts together there is no 55 danger of getting the reflector in crooked and then crushing it out of shape or spoiling the lamp or its socket as the parts are screwed together, this being a difficulty commonly experienced with battery hand lamps 60 now on the market. The bright surface of reflector 22 need not be touched by the fingers, and so keeps bright even though it may have a delicate and highly polished face.

65 Other objects and advantages of the con-

struction described will be apparent to those skilled in the art, and changes in details of the several parts are contemplated within the scope of the invention as defined by the appended claims.

In a companion application, Serial No. 371,599, filed April 6, 1920, the support for the lamp socket may be of rigid material and detachable from the casing. Many features herein disclosed are claimed therein, 75 broadly.

I claim:—

1. In a battery hand lamp, the combination of a casing, a battery of dry cells therein, a lamp connected with one terminal of 80 said battery, a socket in which said lamp is threaded, a yielding disc of insulation supporting said socket, a reflector insulated from said socket and removable therefrom, and means for establishing electrical connection from the other terminal of said battery to said socket.

2. In a battery hand lamp, the combination of a battery, a lamp in operative relation thereto, a casing for said battery, a soft 90 rubber disc closing the end of said casing and in which said lamp is mounted, and a reflector for said lamp removable therefrom without disturbing the operative relation of said lamp to said battery, substantially as 95 described.

3. In a battery hand lamp, the combination of a battery, a casing therefor, a lamp connected with said battery, a socket for 100 said lamp, a yielding disc of insulation closing the end of said casing and supporting said socket, a reflector insulated from said socket and movable away from said lamp and socket, said reflector having a central opening through which the lamp bulb will 105 pass, means for adjustably supporting said reflector in operative relation to said lamp, and means for completing the battery circuit through said lamp.

4. In a battery hand lamp, the combination of a casing having a threaded metal end, a battery therein, a lamp in operative relation to said battery, a socket for said lamp, an insulating disc threaded to the metal end of said casing, said disc being 115 yielding in character to cushion any impact of the battery on said lamp, a reflector insulated from said socket, and means for moving said reflector with respect to the said socket when the distribution of light 120 from said lamp is to be altered.

5. In a battery hand lamp, a casing, a battery therein, a lamp contacting with one terminal of said battery, a socket for said lamp, a yielding disk of insulation supporting said socket in said casing and cushioning any impact of the battery on the lamp and a reflector insulated from said socket and removable therefrom, substantially as 125 described.

6. In a battery hand lamp, a casing, a battery therein, a lamp connected with one terminal of said battery, a socket for said lamp, a yielding disk of insulation permanently secured to said casing and supporting said socket, and a reflector insulated from said socket and removable therefrom, substantially as described.

7. In a battery hand lamp, the combination of a metal casing having a threaded front end, a battery therein, a lamp con-

nected with said battery, a socket for said lamp, an insulating disc threaded to the front end of said casing and supporting said socket therefrom, a reflector for said lamp having a central opening through which the bulb of said lamp will pass, and means for moving said reflector while maintaining operative relation between said battery and said lamp.

In testimony whereof I affix my signature.

CHARLES F. BURGESS.
